UNITED STATES PATENT OFFICE.

ALLAN O. CARPENTER, OF CORNING, NEW YORK, ASSIGNOR TO INGERSOLL-RAND COMPANY, OF JERSEY CITY, NEW JERSEY, A CORPORATION OF NEW JERSEY.

VERTICAL COMPRESSOR.

Application filed July 10, 1925. Serial No. 42,634.

To all whom it may concern:

Be it known that I, ALLAN O. CARPENTER, a citizen of the United States, and a resident of Corning, in the county of Steuben and State of New York, have invented a certain Vertical Compressor, of which the following is a specification, accompanied by drawings.

This invention relates to vertical compressors, pumps and the like, but more particularly to the cylinder construction of multi-stage compressors.

The objects of the invention are to enable the cylinders to be constructed in compact block form in order to produce a strong and durable unitary construction, occupying the minimum of space, and especially adapted for small units, which may be applied to portable compressor outfits.

The invention is shown in one of its preferred forms, in the accompanying drawings, in which—

Figure 1 is a longitudinal sectional elevation of a compressor;

Figure 2 is a detail vertical sectional view through the high pressure cylinder on the line 2—2 of Figure 1 looking in the direction of the arrows, and

Figure 3 is a horizontal sectional plan view of the compressor on the line 3—3 of Figure 1.

Referring to the drawings, the compressor comprises the base A of any suitable or usual construction having the crank shaft B mounted therein which may be provided with the pulley C. A low pressure air cylinder D is mounted on the base A and a cross head guide cylinder E is formed integral with the low pressure air cylinder D and arranged alongside the air cylinder. These two cylinders D and E form a block cylinder construction cast in one piece and a water jacket F is provided for both of said cylinders having the water plug or plugs G.

The piston H of the low pressure air cylinder is connected by the connecting rod J to the crank K and the cross head L in the guide cylinder E is connected by the connecting rod O to the crank P.

An air cylinder head Q extends over both the low pressure cylinder D and the guide cylinder E and a high pressure air cylinder R is

formed integral with the said air cylinder head. In assembling the parts the high pressure cylinder R is adapted to be located over the guide cylinder E and the cross head L is provided with the piston S for the high pressure cylinder R. The air head Q is preferably formed with the shouldered seat T adapted to be seated in the end of the guide cylinder E to center the parts with relation to each other. The high pressure cylinder R is provided with the air head U having the intake and discharge valves V and W of any suitable form. The low pressure cylinder D is provided with the intake and discharge valves X and Y of any suitable form.

Air enters at the inlet a through the low pressure cylinder D and is discharged at the discharge outlet b of the high pressure cylinder R.

A discharge passage c connects the discharge outlet d of the low pressure cylinder D with the intake e of the high pressure cylinder E.

The air cylinder head Q as shown is preferably open at the top at f and forms a water tank and a water jacket g is thus provided for the high pressure cylinder and the parts contained in the said air cylinder head Q. Means are provided for connecting the water jacket g and the water jacket F and for this purpose apertures h and i may be provided in the air head guide cylinder casing so that continuous circulation of jacketed water may be obtained.

I claim:

A multi-stage vertical compressor or pump, comprising a base, a low pressure air cylinder mounted on said base and having a cross head guide cylinder formed integral therewith, said air cylinder and guide cylinder being arranged side by side and provided with a water jacket, an air cylinder head extending over both the said low pressure cylinder and guide cylinder and having a high pressure air cylinder formed integral therewith adapted to be located over the guide cylinder, pistons for the cylinders, and a cross head in the guide cylinder connected to the high pressure piston.

In testimony whereof I have signed this specification.

ALLAN O. CARPENTER.
